(57) CLAIM

The ornamental design for a martial arts belt display, as shown and described.

DESCRIPTION

FIG. 1 is a bottom, front, and right side perspective view of a martial arts belt display showing my new design;

FIG. 2 is a right side elevational view thereof;

FIG. 3 is a rear elevational view thereof; and,

FIG. 4 is a top plan view thereof.

The broken-line disclosure of martial arts belts in the views is for illustrative purposes only and forms no part of the claimed design.
